BOTTLE

James M. Guthrie, Pittsburgh, Pa., assignor of
one-third to Joseph C. Keaney, Mount Leb-
anon, Pa.

Application May 20, 1935, Serial No. 22,397

2 Claims. (Cl. 215—7)

My invention relates to bottles, and consists in means for preventing the re-use of a bottle as an original container.

For years and in great number various structures have been proposed to this end, but in most cases the proposed structures have been either commercially impractical or too costly to manufacture and install.

I aim to provide a bottle which, when once used, is permanently disfigured. It is further my object to provide a structure of extreme simplicity—a structure which may be manufactured and used conveniently at practically no more cost than the ordinary bottles in use today.

15 I am primarily concerned with bottles that are closed by means of screw caps or threaded closures, and the invention is particularly directed to a novel organization of bottle and screw cap.

In the accompanying drawing Fig. I is a fragmentary view in front elevation of a bottle embodying the invention; Fig. Ia is a fragmentary view, showing to larger scale the neck of the bottle shown in Fig. I; Fig. II is a view in plan from above of such bottle; Fig. III is a view in side elevation of a cap of well-known type, effectively modified, for use with the bottle; Fig. IV is a view of the bottle in side elevation, showing the cap (partly in elevation and partly in vertical section) positioned and ready to be secured upon the bottle; Fig. V is a view comparable with Fig. IV, showing the completed assembly of bottle and cap; Fig. VI is a fragmentary view of a bottle neck to larger scale, and illustrating a cap of modified structure screwed into place on such neck and ready to be locked thereon in accordance with my invention; Fig. VII is a view of the last-mentioned cap in plan from above; Fig. VIII is a view comparable with Fig. VI showing the completed assembly; Fig. IX is a view similar to Fig. VI, showing another modification in cap design; and Fig. X is a sectional view, taken on the plane X—X of Fig. IX.

Referring to Figs. I to V of the drawing, a glass bottle 1 is fragmentarily indicated. The bottle 45 is provided with a neck 2 whose upper portion is provided with external threads 3 for co-operation in well-known way with a screw cap or closure. A detent or lug 4 is integrally formed with the glass neck of the bottle; the detent projects 50 angularly from the neck of the bottle, and is weakened for ready and clean fracture, advantageously by means of a surface cut (such as may be made by a diamond-pointed cutter), as indicated at 5 in Fig. II and Ia. The detent is of adequate strength to remain integrated with the

bottle until it is intentionally broken on a predetermined line or plane of cleavage.

In Fig. III a bottle closure 6 is shown. This particular closure comprises a cap that includes a compressible gasket 7, cf. Fig. IV; the cap includes a cylindrical skirt portion 8 of relatively soft sheet metal, such as aluminum; the skirt extends downward from the top wall 9 of the cap and terminates in a peripheral bead 10, and a recess or notch 11 extends upward or inward from the peripheral edge or bead of the skirt. Save for the notch 11, the structure of the closure 6 is substantially identical with a type of cap widely used in the art today.

In closing or sealing a bottle filled with the 15 desired contents, the cap 6 is placed over the neck of the bottle as shown in Fig. IV, the beaded notch or recess 11 being brought to registry with the detent 4, so that the cap may be pressed downward over the mouth of the bottle, to compress the gasket 7 into bottle-sealing position. While the parts are so arranged, a thread is impressed in the skirt of the cap, such, for example, as in the manner fully explained in Patent No. 1, 684,892, granted September 18, 1928, 20 to John E. Sharp. The threads impressed in the skirt of the cap (note Fig. V) engage the threads 3 on the bottle neck, whereby the closure is secured in bottle-sealing position. Lying within the notch 11, the detent 4 serves normally to prevent the cap from being rotated for removal from the bottle.

When in the hands of the consumer, it becomes desirable to open the bottle, the detent 4 is tapped sharply with the heel of a bottle opener or other 25 handy implement, whereby the detent is fractured on the definite, predetermined line of weakness adjacent its base and falls free of the bottle. It will be noted that the diamond cut 5 (or other surface scoring) is provided within the periphery 30 of the applied cap. Thus, the detent or lug 4 is caused to break on a plane of cleavage so located with respect to the periphery of the skirt of the closure that once the lug has been broken the cap may be readily removed.

The destruction or rupture of the detent leaves a stub apparent upon the neck of the bottle. If the bottle is refilled with an illegitimate product and sealed, the presence of the stub, or the absence of the expected detent, on the bottle neck 35 quickly signifies to a prospective purchaser that the bottle is not an original.

The usual finish bead 20 on the bottle neck 3 may be of interrupted continuity beneath the lug 55

4, as indicated at 40 in Figs. I, IV, and V, or it may be continuous throughout the circumference of the neck, as indicated in Fig. Ia.

It will be readily understood that a small recess 5 may be formed in a bottle mold already in service, whereby the bottles blown to shape therein will be each provided with a detent 4. Manifestly, no substantial change in manufacturing procedure is required for the production of my bottle. Indeed, my non-reusable bottle may be manufactured for practically the same cost as the ordinary bottles they are intended to replace. And clearly it is a simple matter for the engineer so to change existing cap-making machines that 10 the notch or recess 11 may be formed in the otherwise standard closure 6. Accordingly, advantages long desired may be enjoyed with no appreciable increase in cost of manufacture, with no substantial increase in the quantity of materials required, 15 and with no significant departure from the usual bottle-sealing practice. Additionally, the practice of my invention does not materially alter the appearance of the bottle, which is an item of concern in the case of those industries which 20 have developed highly ornamental bottles in which to sell their products.

Another well-known form of screw cap or closure is supplied with the threads already in the skirt of the cap. The cap 6a in Fig. IX is illustrative. This form of cap, due to its rigid, threaded side wall or skirt, must be screwed into bottle-sealing position. In adapting such cap to this invention, I provide a band 12 of hard sheet metal, such as steel; the band 12 is provided with 25 a flange 14 extending along its upper edge, and it includes a window 13, as shown; when the cap 6a is screwed tightly into bottle-sealing position, the band 12 is adjusted in the position shown in Fig. IX, with the detent 4b projecting through the window 13 and the flange 14 overlying the 30 peripheral bead 10a of the cap; then the ends of the band are united by spot-welding, or by bringing the ends of the band into overlapping relation (cf. Fig. X), and then pressing them inward 35 in the direction of the arrow, forming a so-called ship-joint. The closed band 12 does not directly prevent rotation of the cap 6a, but it does prevent the cap's removal. That is, rotation of the cap causes the bead 10a to bear against the flange 14, 40 whereby the band 12 is raised until the lower edge of the window 13 bears against the nether face of the detent 4b. Further rotation of the cap is manifestly prevented, until the detent 4b is broken away. The detent 4b is weakened at 45 50 (Fig. X) by a diamond cut or other surface scoring adjacent its region of integration with the bottle neck, whereby it may be cleanly broken off to permit closure removal.

In further refinement, the rigid walled type 55 of screw cap is flared outward at its peripheral edge, as shown in Fig. VI and VII; the outwardly flaring portion 15 is crimped radially of the cap, or is otherwise formed to include a recess 11a.

The threads on the bottle are so arranged or designed that, when the cap is run into bottle-sealing position, the recess 11a will be located above the destructible detent 4a on the bottle neck. When the parts are so positioned, the annular, flaring portion 15 of the cap is pressed downward, and into snug engagement with the neck of the bottle, as shown in Fig. VIII. Manifestly, the detent 4a then serves normally to prevent removal of the screw cap. In such way 10 the peripheral rim portion of a threaded bottle closure may be adapted, after the closure has been installed in bottle-sealing position, to enter cooperative relation with a frangible lug on the neck of the bottle. 15

Means are provided to effect the automatic destruction or fracture of the detent, when the cap is intentionally unscrewed. Advantageously, the upper face of the detent 4a is tapered, as shown in Fig. VIII, and the beaded edge portion 20 15a of the cap is so formed and arranged that, when the cap is unscrewed, the edge 15a rides with wedging effect over the detent, causing its rupture. The detent 4a advantageously is weakened by means of a diamond cut, or the body of 25 the detent is otherwise weakened after the bottle has been blown and cooled.

Notice is hereby given of my co-pending application Serial No. 52,473, filed December 2, 1935, and covering a bottle provided with a frangible 30 lug.

I claim as my invention:

1. In a glass bottle having a threaded neck and a frangible lug integrally formed with and projecting angularly from said neck at a point below 35 the mouth of the bottle, the combination of a screw closure including a threaded skirt portion and a peripheral rim portion initially so formed that the closure may without interference with said lug be screwed into bottle-sealing position 40 on said threaded neck, said peripheral rim portion being adapted, when the closure has entered said bottle-sealing position, to yield downward into position of cooperation with said lug.

2. A glass bottle sealed with a bottle closure 45 including a cap having a skirt portion extending downward over the bottle neck and in threaded engagement therewith, a lug integrally formed with the bottle neck and projecting angularly 50 therefrom and cooperating with said skirt portion to secure said cap against closure-removing rotation, and said lug (as the bottle is used in commerce as a sealed container for a saleable product) having a weakening surface scoring 55 adjacent the region of angular emergence of the lug with the bottle neck and radially within the effective compass of the skirt of said closure, whereby the lug may be intentionally broken away, leaving the resulting plane of fracture so located within said skirt that said cap may be 60 readily rotated to open said closure.

JAMES M. GUTHRIE.
